US0D1054321S

(12) **United States Design Patent** (10) Patent No.: **US D1,054,321 S**
(45) Date of Patent: ** Dec. 17, 2024

(54) **ALL-TERRAIN VEHICLE**

(71) Applicant: **Ensenor Enterprises Limited**, Nicosia (CY)

(72) Inventors: **Volodymyr Shkolnik**, Kyiv (UA);
Sergei Samokhvalov, Kyiv province (UA)

(**) Term: **15 Years**

(21) Appl. No.: **35/510,784**

(22) Filed: **Aug. 12, 2020**

(80) **Hague Agreement Data**

Int. Filing Date: **Aug. 12, 2020**

Int. Reg. No.: **DM/211221**

Int. Reg. Date: **Aug. 12, 2020**

Int. Reg. Pub. Date: **Nov. 20, 2020**

(51) **LOC (14) Cl.** **12-07**

(52) **U.S. Cl.**

USPC **D12/1**

(58) **Field of Classification Search**

USPC D12/1, 12
